CALENDAR

Robert Merlin Bryant, Baltimore, Md.

Application March 29, 1948, Serial No. 17,729

4 Claims. (Cl. 40—115)

1

This invention relates to calendars and more particularly to those having dating that is mechanically operated.

In a particular form of mechanical calendar, the numerals indicating the days of the month are arranged consecutively on members that are rotatable separately to show any number from 1 to 31 inclusive for designating the date. These numbers appear inside a frame located suitably for observation. Adjacent these numerals, is another member with the names of the months positioned thereon, subject on rotation to appear in another frame. Another member and frame is similarly used to designate the names of the days of the week. These members are manually operated, to show the month, day of the week and date in a single line. While this arrangement is convenient and avoids the need for the pad of 12 leaves of months commonly employed, which are relatively wasteful, it requires a relatively cumbersome mechanism, is heavy, and is limited to the conventional dating. For instance there is no way of determining from such a calendar the identity of holidays, by any convenient manner.

In this invention, the calendar is preferably in the form of a flat main sheet of stiff material suitable for hanging on a wall or placing on a desk or other flat surface. It has various discs in back that may be rotated to present themselves for observation in openings or windows provided in the main sheet, in such positions as to disclose, a number for the date, a name for the day of the week, and another marking for the month, and the number of days therein. In addition there is a space that enables the dates on which holidays exist, to present a code sign that can be readily recognized as a holiday. Further than that, an arrangement is provided for retaining the calendar in its monthly period, in a most effective manner, but readily changeable to suit a change to a new month display.

There is in addition to the above advantages, a color code which is set out for each individual month and is usually applied to a handle which is used to turn the calendar to the next month. This same set of colors is set out above the slot on which the days of the week appears. In use the color of the month is noted and the day of the week will be found below the same color set out above its proper day.

In all, however the operation of the device is very simple and the cost of construction relatively economical. It also is very readable and attractive.

For a better understanding of the invention reference is made to the appended drawings which disclose a particular form of the invention by way of example. The description of this form of the invention is given in the following speci-

2

fication, while the scope of the invention is emphasized in the claims.

Referring to the drawings:

Figure 1 is a front view of a calendar embodying this invention, with the calendar raised slightly out of its base;

Figure 2 is cross sectional view taken along line 2—2 of Figure 1;

Figure 3 is a detail of the day of the week and 10 monthly numerals set out on the disc used in this embodiment;

Figure 4 is a detail indicating the construction of the operator used in this embodiment with portions in section to indicate the manner of its 15 attachment to the discs;

Figure 5 is a detail of the months of the year and number of days per month set out on the disc used in this embodiment;

Figure 6 is a sectional view taken along line 20 6—6 of Figure 1.

Similar reference characters relate to the same parts throughout the drawings.

In the structure shown in the drawings, a casing 10 of two sheets 12 and 92 of cardboard, plastic or other material suitable for the purpose, fastened so as to contain the moving parts of a movable calendar. The front sheet 12 of this casing is marked up with the designation of the year in suitable numerals 11. These may be 25 placed in any conspicuous position or location on this front, and preferably away from other readable portions of the calendar. A slot 13 of arcuate contour is cut out of the front sheet 12 near the top and about its vertical axis. This slot 13 serves as a window for observing the names of the months, 14 (one at a time), as well as the number of days in the specific month as the disc 15 on which they are printed is rotated. Another slot 16 is arcuately cut out of the front 30 sheet 12, and situated below the slot 13 and is preferably longer, to allow the indication of the seven days, 17, of the week in the window formed by it. These days, 17, of the week are printed on the periphery of a disc 18, located between the front and back sheets of the casing 10. Another 35 smaller window 20 is cut out of the front sheet 12 and located under the previously mentioned window 16. This window 20 discloses the date numerals, 50, which are also printed on the disc 18 below days, 17. A vertical window 19 is cut out of the front sheet 12 and is made relatively long in order to disclose the marks 21 of a special code used to identify holidays, or other special occasions during the year. These marks 21 40 are preferably colored and printed on the disc 15, as part of the months specifically needing them. Perforations 22 are placed in disc 18 to allow the marks 21 to be seen at predetermined periods. Suitable perforations 52, aligned with each other 45 in the sheets 12 and 92 of the casing 10 serve as a

50

55

60

bearing for a stud 23 to project through. This stud 23 has a knob 24 which presses against the front sheet 12 and is used for manipulating the stud 23 and disc 18. The stud 23 is provided with a square shoulder 45 and washers 25 that engage with the square hole 58 of the disc or member 18, so that the rotation of the stud 23 will also rotate the disc 18. A printed circular row 26 is marked with small colored circles, black 27, brown 28, white 29, red 30, yellow 31, green 32, and blue 33 in the areas partitioned off by the lines 34 as indicated. These areas are stationary and are directly above and register with the spaces in which the days, 17, of the week appear when set in their various predetermined arrangements, behind the windows. The disc 15 has a superimposed colored circle tab 35 for each month. The colors of these tabs 35 have certain relations to the circles in the circular row 26, which will be explained later on. Holes 36 in the sheets of the casing 10 serve to facilitate the hanging of the calendar on a nail on a wall and at the same time align with a hole in the month disc 15. The nail in passing through the holes holds the month disc locked in one position. The month therefore selected at the time, will be kept locked in position during the month of its use. A slot 40 in the channel 41 of the stand 42 may be used for same purpose, when the calendar is supported in the channel 41 of a stand 42. Space 55 is provided on the front sheet 12 to enable announcements 43 to be shown.

The operation of the calendar is as follows: The user first sets the selected month 14 by moving the disc 15 to the window 13. This brings the colored tab 35 into the user's view. This color tab 35 is compared with the colors of the circles 27 et seq. over the days 17, after the date numeral 50 is shown in its window 20. As an example, assuming that July is the month selected, and the color it has is black. Then the knob 24 is turned until the date "4" is disclosed at the window 20. This turns the days 17 and reregisters them under the colored circles in the circular row 26, which happens to align the day Sunday under the black circle. The mark 21 will show through hole 22, showing that Sunday, July 4th is a holiday. If we turn the month February into place, the color "red" appears in its tab 35. Then if the knob 24 is turned until "22" comes into view, the days 17 will rotate until Sunday is under the "red" circle of the circular row 26. When this is done, it will be noticed that another mark 21 has appeared on the calendar, in the hole 22 and window 19. This mark "21" indicates that this date is also a holiday. Similarly the calendar is changed for other months, and numeral dates. The setting of these two items also enables the reader to determine the day of the week automatically.

The colors of the tabs 35 are arbitrarily made as follows: January, black; February, red; March, yellow; April, black; May, white; June, green; July, black; August, red; September, blue; October, brown; November, yellow and December, blue.

While but one general form of the invention is shown in the drawings and described in the specifications, it is not desired to limit this application for patent to this particular form or in any other way otherwise than limited by the scope of the claims, as it is appreciated that other forms of construction could be made that would use the same principles and come within the scope of the appended claims.

Having thus described the invention, what is claimed is:

1. A calendar comprising a casing comprised of a front sheet and a back sheet, said front sheet having a plurality of axially aligned windows, a plurality of discs in said casing between said front and back sheets, a hub element extending through the center of said casing and discs, a knob secured on said hub element and manually operable in front of said front sheet to rotate one of said discs, the first of said discs bearing the names of the months selectively appearing through the first of said windows, the second of said discs bearing the names of the days of the week and the numerals of the days of the months selectively appearing through two more of the respective windows, and said first mentioned disc bearing additional symbols to indicate special feast days, said symbols coinciding with openings through said second mentioned discs and appearing through the last of said mentioned windows.

2. A calendar as set forth in claim 1, the other of said discs having extensions extending peripherally and radially thereof for rotating said disc to select the name of the month appearing through said first mentioned window.

3. A calendar as set forth in claim 1, the other of said discs having extensions extending peripherally and radially thereof for rotating said disc to select the name of the month appearing through said first mentioned window, said last mentioned disc having openings therein directly beneath and radially situated with respect to each of said extensions, coinciding with openings through said front and back sheets, to mount said calendar on a nail through each respective opening to immobilize said disc in the position of the selected month appearing through said first mentioned window.

4. A calendar as set forth in claim 1, the other of said discs having extensions peripherally and radially thereof for rotating said disc to select the name of the month appearing through said first mentioned window, said extensions also having differently colored indicia, said front sheet bearing a circular row of colored indicia corresponding to said colored indicia carried by said extensions, said circular row indicia appearing directly above the window showing the days of the week, whereby correspondingly colored indicia on said extensions and in said circular row will indicate corresponding month of the year and name day of the week.
